PROCESS FOR UTILIZING WASTE
VEGETABLE MATERIAL

Robert B. Arnold, Stonewall Courts, Va., assignor
to Tobacco By-Products and Chemical Cor-
poration, Louisville, Ky., a corporation of Dela-
ware

Application November 10, 1932, Serial No. 642,011

3 Claims. (Cl. 23—48)

This invention relates to a process for utilizing waste vegetable material. The invention more particularly relates to the recovery of values from waste vegetable material derived from land plants which when treated as hereinafter described will evolve a relatively high proportion of volatile, combustible materials and which are relatively high in potassium compounds. A typical waste material of this kind is waste tobacco residue. There are some other vegetable materials to which the process is applicable, such, for example, as cotton hulls.

One of the principal objects of the present invention is to provide a process which will enable a nicotine extraction plant to recover from its residues of tobacco material, after the extraction of the nicotine, the alkaline material which, of necessity, is used in the process of extracting nicotine, and at an economical cost.

A further object of the invention is to recover from the said residues the potash content at a cost which will be commercially economical.

With these general objects in view and others which will be obvious to those skilled in the art from the description hereinafter, the invention consists in the features which will be more fully pointed out hereinafter.

In the accompanying drawings is illustrated an apparatus which may be used in carrying out the invention. In these drawings:

Figs. 1 and 1a together constitute a diagrammatic plan view of the apparatus.

Fig. 2 a diagrammatic side view partly in section, on the line 2—2, Fig. 1.

Fig. 3 a similar view on the line 3—3, Fig. 1.

Fig. 4 a similar view on the line 4—4, Fig. 1A.

Fig. 5 a transverse section on the line 5—5, Fig. 1.

Fig. 6 a transverse section on the line 6—6.

Fig. 1.

Fig. 7 a diagrammatic side view partly in section of the preliminary concentration apparatus.

Figs. 8, 9, and 10 horizontal sections on the lines 8—8, 9—9, and 10—10, respectively, of Fig. 7.

Fig. 11 a detail vertical section, partly in elevation, to illustrate the quenching apparatus, and

Fig. 12 a flow sheet to illustrate more fully the steps of the process in their relative order.

It has been common in the art heretofore to recover some of the values from waste tobacco material, for example, nicotine and ammonia accompanying it, the nicotine and ammonia being recovered usually as sulphates. In order to free the nicotine from the waste tobacco material it

is usual to comminute the tobacco material and then treat it with a solution of an alkaline material, usually lime water, and subject it to what may be termed a low temperature steam distillation. As a result of this treatment, the tobacco residue, freed of its nicotine and ammonia, as well as of practically all its moisture, is obtained in a substantially dry condition. The alkaline material supplied to the tobacco to release the nicotine remains with the residues.

It has been recognized that the dried residues from the nicotine extraction plant have an agricultural value, not only on account of the alkaline earth compounds and a small amount of nitrogen, but also and more particularly because of the alkali compounds, particularly potash, carried by the residues. However, the quantity of such dried residue is so great and the cost of transportation is so high because of its bulk that there is difficulty in disposing of such residues for agricultural purposes at a price such as to lower the cost of making nicotine.

Many attempts have been made to recover the values from plant refuse, such as tobacco waste, and some other plant material, but without commercially successful results. It has been found that the tobacco residues are exceedingly difficult to burn. When fired in small piles in the open air they can finally be burned to ashes, but in the attempts which have heretofore been made to burn them in retorts or furnaces it has been considered necessary to combine some additional fuel, such as fine coal, with the refuse in order to burn them in furnaces of reasonable capacity, or to use fuel to heat the retorts externally.

On account of the cost of such methods of burning it has usually been the practice, in disposing of such plant refuse, to attempt to recover not only the potash but also volatile products which are evolved in the burning, in the same way that pyroligneous acid is derived in the burning of wood to charcoal and then worked further to separately recover the various organic chemicals.

These attempts, as far as known to me, have not proved commercially successful, because of the necessary investment in the apparatus required, and the low and uncertain market value of the products obtained from the volatiles. Owing to the inability by prior methods to obtain complete carbonization of the potassium compounds there is also present in the final product a small percentage of potassium hydroxide, as well as some potassium cyanide formed by the combination of

the fused potassium carbonate with the carbon and nitrogen. This makes it necessary to treat the potassium compound or the solution of the same by further steps in order to remove the potassium cyanide, because it is a dangerous ingredient in the product on account of its highly poisonous nature. Applicant has discovered that by abandoning any attempt to save the volatile products of the destructive distillation of the tobacco residues, as a base for the recovery of organic chemicals and using a part of those volatile products which are combustible as fuel directly in a kiln containing the tobacco residues, with a restricted access of air, and burning all the remainder of such volatile combustibles immediately on their escape from the kiln without permitting them to cool essentially, and with sufficient air to complete the combustion without undue cooling of the products of combustion, the heat value thereby developed in the two stages is not only more than sufficient to carry on the destructive distillation of the residues at the first stage to the point of obtaining a good porous fixed carbon product in which the inorganic compounds are well disseminated, but is sufficient to carry the combustion of the combustible volatiles to completion and leave an excess of heat in the second stage which will more than suffice to carry out the concentrating and evaporating operations necessary in recovering the alkali compounds in solid form. The fixed carbon residue forms a concentrated product of sufficient value for agricultural purpose to allow it to be sold at a profit, and in addition is good as a starting material to be extracted with water for the recovery of the potassium and sodium compounds. After extraction the solid residue consisting of the fixed carbon and the alkaline earth compounds, particularly calcium carbonate, not only has a marketable value for agricultural purposes, but can be dried and burned to convert practically all of such carbonates into oxides, the fixed carbon having sufficient heat value to burn the carbonates to oxides and to dry the wet material coming from the extracting apparatus before it enters the calcining kiln.

A further and most important feature of the invention consists in simultaneously concentrating the alkali solution from the extraction step and converting any caustic portion thereof into carbonate by the direct contact of the solution with the hot gases relatively rich in CO₂ produced by the complete combustion of the combustible volatile products escaping the destructive distillation kiln as hereinbefore described. As this step of the process can be conducted in an apparatus which is highly resistant to chemical action and yet not expensive, as for example a scrubbing tower whose exposed parts are chemical brick, it becomes commercially possible to carbonate the caustic alkali and thereby produce a marketable solid salt free from objectionable deliquescent and caustic ingredients, and also free from the dangerous potassium cyanides.

It is an important advantage of the present invention that the calcium of the lime used in treating the tobacco as aforesaid is recovered in a desirable form either as a carbonate, under one method of treatment, or as an oxide under another method of treatment, in accordance with the invention. When recovered as an oxide, it may again be used for treatment of further waste tobacco material. Since by the present invention the calcium oxide may be produced at the nicotine extraction plant at a cost less than that of the

cost delivered of the original lime the present invention when employed at the nicotine recovery plant becomes an important factor in reducing the cost of producing nicotine. Therefore, in this form of the invention the process of recovering nicotine is in part a cyclic one, since disregarding losses, the lime or other alkaline earth compound used for setting the nicotine free is repeatedly used over again, so that there is a continuous saving on the cost of such alkaline material.

Where the invention is applied to the production of the new product hereinafter more particularly described, the value of this product, which contains the calcium in the form of a carbonate, is a set off for the cost of fresh lime for carrying out the nicotine process and therefore in this way reduces the cost of producing nicotine.

In either form of the invention, the initial steps comprise the treatment of the waste tobacco material with a solution of an alkaline earth compound, usually lime, which may and often does contain some magnesia, then the treatment of the tobacco material with a relatively low degree of heat in a suitable atmosphere to evolve the nicotine, which is carried off and recovered, and to dry the residue of waste tobacco material.

The residues thus obtained carry all the calcium and any magnesium which was applied to the tobacco material, as well as any calcium or magnesium which was in the tobacco originally, and also carry an appreciable amount of potassium compounds.

The said residues are subjected to a low temperature destructive distillation process in a suitable kiln to carbonize the vegetable matter and drive off all volatile and low temperature vaporizable matter, burning a portion only of the volatile combustible material in the kiln, to furnish the heat for the destructive distillation, while avoiding the combustion of all such volatiles or of any fixed carbon. In the best embodiment of the invention the destructive distillation is accomplished by igniting the tobacco material and burning a portion of the volatile matter, with controlled restricted access of air, the hot gases of this combustion passing into contact with fresh tobacco material in the absence of air. The temperature of this destructive distillation is so controlled that first the volatile components and those vaporizable at a low temperature are driven off and thereafter the remaining material is carbonized to form a charcoal, it being important, however, and an essential feature of the present invention that the material be heated about to the temperature at which potassium salts will fuse but most advantageously not above this temperature, whereby there is formed some ash and also a granular mass of carbon constituting substantially all of the fixed carbon of the tobacco material from which it was made, this mass of carbon carrying potash derived from the potassium salts of the original vegetable material, this potash not being occluded in the carbon but so carried by the latter that it is readily extracted, as for example, by percolation, if desired. The solids from the destructive distillation step of the process are quickly quenched to prevent continuing combustion of the carbonaceous material when exposed to air, but not sufficiently to cool the solids to atmospheric temperature, and are, while still warm, subjected to an aqueous extraction step to dissolve out and thereby extract all water-soluble ingredients, these being principally potassium compounds accompanied by some sodium compounds. Although these compounds

are mostly salts, for example carbonates, there will be present, usually, some hydroxides, as for example, hydroxides of potassium or sodium, or both, with a small amount of potassium cyanide.

5 During extraction, the solution is separated from the solids, and then the solution is subjected to a preliminary concentration step, by bringing it into direct contact with hot combustion gases rich in CO₂ whereby any hydroxides in the solution are converted into carbonates and a considerable portion of the water of the solution is evaporated and carried off by the departing gases. Also the potassium cyanide is carbonated, the acid passing off. Thereafter the concentrated aqueous solution is evaporated to recover the potassium and sodium salts in solid form.

The above-mentioned preliminary concentration and final evaporation is done with heat derived from the tobacco material itself. The hot 20 gases and vapors driven off from the destructive distillation zone are passed into a combustion chamber together with considerable additional air and thereby are completely burned, thus raising the temperature of the gases and producing a relatively large amount of CO₂. The hot combustion gases, rich in CO₂, are passed first through the evaporating apparatus thus applying the heat for the final evaporation of the concentrated solution, and then into direct contact with the aqueous solution to be concentrated. This concentration may be done by passing the hot gases 25 in contact with a rain or traveling film of the aqueous solution so that the CO₂ of the gases may react on the hydroxides and cyanides in the solution to convert them into carbonates; may supply heat to the solution to evaporate some of its water; and by changing from an unsaturated to a partly or wholly saturated condition may carry off some water in that way.

40 The solids from the extraction step, freed from their water-soluble ingredients consists principally of fixed carbon and carbonates of calcium or magnesium, or both, the fixed carbon being mostly in a granular condition, the granules being 45 porous and carrying the carbonates of calcium, or magnesium, or both. As these solids are wet when discharged from the extraction step, they are dried by using some of the hot gases derived from the tobacco material.

50 The dried solid product thus obtained is a black granular material, the granules being porous and comprising fixed carbon and carbonate of calcium or carbonate of magnesium, or both sometimes, with small amounts of other ingredients.

55 While the percentage composition of this product varies considerably on account of variation in the composition of the tobacco waste, a typical analysis of such product is as follows:

Percent by weight	
Carbon	20
Calcium carbonate	60
Magnesium carbonate	10
Sand, etc.	10

65 In this new product the alkaline earth carbonates are within the granules thereby being finely divided and well dispersed, so that they are readily attacked by reagents for calcium and magnesium.

70 This product is very efficient as a case hardening material for case hardening steel, because of the intimate association of the calcium and magnesium carbonates with the carbon and the porous nature of the latter. Also it is especially 75 advantageous as a soil conditioner on account of

its fluffy nature, its high content of carbonates of calcium and magnesium and the porous nature of the carbon, which in the soil serves to store moisture and maintain an alkaline condition of such soil moisture. The fine granular condition of the material makes it convenient to apply the material to the soil by hand or by machinery so as to secure a uniform distribution of the calcium and magnesium carbonates in the soil. Instead, however, of disposing of this new product 5 as a commodity, it may be treated further to burn the carbonates of calcium and magnesium to oxides. This is possible economically because the fixed carbon is present in sufficient amount to furnish all the heat necessary to drive off the 10 carbonic acid and thereby produce the required oxides. Therefore, the new product described 15 above is ignited and supplied with sufficient air to burn completely all its fixed carbon. The resulting calcium and magnesium oxide, with some 20 impurities, such as sand, is cooled and forms an alkaline product which may be used in the nicotine extraction plant for forming the alkaline solution for treating further waste tobacco material to set free the nicotine. 25

Since the cost of recovering this alkaline product is less at the nicotine extraction plant than the cost of fresh lime burned elsewhere and transported to the plant there is a saving in using it, and thereby a reduction in the cost of producing nicotine. 30

The plant for carrying out the process will now be described.

Referring to the drawings, and particularly to Figs. 1 and 1A, A indicates a rotary carbonizing or destructive distillation kiln, into which the dried refuse tobacco material from the nicotine extraction plant enters through a pipe 10 at one end, (Fig. 3), and from which the resultant solids are discharged at the other end into the 35 conveyor 11 which carries the solids through a cooling chamber 12, provided with a spraying device 13 and vapor outlet 13¹, to a distributing conveyor 14 by which the solids, still warm but not incandescent, may be discharged into any 40 one of a series of extraction vats, C. The kiln A is lined with fire-brick, as shown in Fig. 5. The gases and vapors from the carbonizing kiln A are discharged into a combustion chamber, indicated at B, where, by a controlled admission of 45 air through suitable inlets, such as indicated at b, which may be provided with dampers, not shown, the combustion is completed and a large amount of hot CO₂ gas is produced. In the extraction vats C the solids from the carbonizing kiln are percolated with water, which is moved 50 from vat to vat by a pump, indicated at c. The extracting apparatus will be more fully described hereinafter. Upon the completion of the extraction step, the solution is pumped off and the 55 solid residues are discharged, in this case by hand, onto an apron c¹ down which the residues slide to a conveyer d which may be rotated in either direction as required to convey the extracted residues to a predryer indicated at D and comprising a sloping casing with an enclosed inclined endless belt 15 which elevates the residues through the casing 16 of the predryer and discharges them to a conveyer d¹, the residues on the apron being dried by a current of hot combustion gases entering at 17 and drawn through the casing 16 by a suction fan d² at the lower end, which finally 60 discharges the gases through the fan discharge pipe 18. The conveyer d¹, may be arranged to discharge the dried residues into a suitable 65

container, not shown, these residues constituting the new product hereinbefore referred to as suitable for case hardening and agricultural uses.

Where however, the product is to be burned to completion to produce the calcium and magnesium oxides, the conveyer d^1 , is caused to discharge into a feeding conveyer e which feeds the dried residues through a gas exit box e^1 of a high temperature rotary kiln E . The gas exit box 10 connects with a stack F . There may be a duct 17^1 from the stack F to the inlet 17 of the pre-dryer D , to utilize the hot gases from the calcining kiln, if desired. The rotary kiln E is lined with fire brick, as indicated at 19 , Fig. 6, and has 15 fire brick shelves 20 for elevating and dropping the residues. The completely burned product from this kiln, consisting chiefly of calcium and magnesium oxide is discharged to a conveyer g which may discharge the product into either of 20 the two vats G^1, G^2 in which alkaline solution for treating tobacco material may be prepared by adding water and agitating the mixture to form the hydroxides, one vat being used to make such mixture while the other is being supplied 25 with the solids by the conveyer g . The alkaline solution when prepared may be run to the liming vats of the nicotine extraction plant by suitable piping, not shown.

The solution of potassium compounds and the 30 like produced at the extraction apparatus may be pumped by the pump c to either of two settling tanks, each forming a part of an apparatus for preliminary concentration of the liquid from whence it is taken to be evaporated to a sludge, 35 and then cooled and centrifuged to obtain the crystals. In the best embodiment of the invention the concentrating and the evaporating apparatus are in duplicate sets, which work in alternation, so that when one set is being cleaned, the 40 other may be working.

In the plant illustrated in the drawings, the preliminary concentration is carried out alternately in that part of the concentration apparatus indicated at H, H^1 , each of which, in the present 45 embodiment of the invention, is similar to a tower gas-scrubber, but contains some modifications, to be pointed out hereinafter. Each scrubber apparatus comprises an external casing 21 , of suitable metal, such as iron or steel, having 50 a chemical-proof lining 22 , which is also a poor thermal conductor. This lining may be of tile. To still further retain the heat the casing may be provided on its exterior with a jacket of thermal insulating material (not shown). Within 55 the casing is a checker work 23 , of chemical brick which rests on a series of arches of the same kind of brick, which arches are indicated at 24 , Figs. 7 and 10, whereby an inlet chamber 25 is formed at the lower end. The checker work 60 has its diameter reduced at its upper end to form an exit chamber 26 to permit the free escape of gases from the checker work, the bottom of this chamber being closed at one side only by a masonry floor as indicated at 27 , Figs. 7 and 8, 65 at which side a tight vertical baffle wall 28 , is provided. The discharge stack connects with the space between the baffle wall and the outer wall. The top of the chamber is closed by a head 29 , which may be removed when necessary for 70 repairs or cleaning. Also the casing is provided with cleaning outlets and caps therefore, as indicated at 30 , Fig. 2, to permit access to the various parts of the exit chamber.

The exit chamber is connected by an exhaust 75 pipe k, k^1 , to the suction side of a fan K, K^1

whose discharge side is connected to a discharge pipe k^2, k^3 , controlled by an adjustable plate damper k^4 , Fig. 2.

The inlet chamber 25 at the bottom of each scrubber of the concentrating apparatus is in 5 communication with the combustion chamber B of the destructive distillation apparatus, through the tubes of an evaporating pan L, L^1 , one for each concentration apparatus H, H^1 , and through a suitable conduit l, l^1 . The evaporating apparatus is constructed as follows:

From the combustion chamber B , two flues advantageously of masonry, extend in opposite directions, as indicated at l^2, l^3 , respectively. Each flue serves as a header to distribute combustion gases to a series of tubes l^4 passing through a closed pan which forms the evaporating chamber, the walls of this pan being indicated at 31 , Fig. 2. The pan has an opening in its top, closed by a tight cover 32 . The tubes l^4 discharge 20 into a header box l^5 from which the conduit l , or l^1 , leads the gases to the inlet chamber 25 at the bottom of the scrubber device of the respective concentration apparatus, as shown in Fig. 10.

The inlet chamber 25 is liquid tight at its bottom to serve as a catch basin, and has an outlet connected to piping which will conduct liquid to the corresponding settling tank. Where the scrubber device H or H^1 has the bottom of the chamber 25 higher than the top of the evaporating pan L, L^1 , there may be piping connecting the outlet from the chamber 25 with its respective evaporating pan, but this may be omitted if desired. Also there is a connection to the respective settling tank. In the present embodiment 35 of the invention both sets of piping are shown, and are as follows: The outlet of the chamber 25 is connected to a T 33 , Fig. 7, and to this T is connected a discharge pipe 34 which leads to the respective settling tank, and is provided 40 with a valve 36 as will be clear from Fig. 1. When the valve 36 is open, liquid from the bottom of the chamber 25 may flow by gravity to the settling tank. To the T 33 , another discharge pipe 35 leading to the top of the corresponding 45 evaporating pan may be provided, as shown in Fig. 1, this pipe having a valve 37 . This discharge system consisting of the pipe 35 and its valve 37 for each concentrating apparatus serves only as an emergency device and may be omitted. 50 In regular practice the liquid is removed from the settling tank by a pump which sends it to the evaporating pan through a pipe system herein-after more fully described in connection with the description of the settling tanks. The settling 55 tank M , or M^1 , has a partition near one end to form a well at that end from which well a pump N or N^1 may take its supply through a suction pipe 38 . The partition is indicated by the dotted line 39 in Fig. 1 and does not extend the full 60 height of the respective tank M or M^1 , as shown in Fig. 2. The pump N discharges through a discharge or supply pipe 40 into a distributing reservoir P , Fig. 7, this reservoir being omitted from Fig. 1 in order not to complicate the showing.

The reservoir has an overflow pipe 41 and a slotted main weir partition 42 , and cross-partitioning 43 , which together form a number of little wells. The weir partition supplies each one of these wells with liquor from the reservoir through the respective weir opening or slot. To the bottoms of the wells are connected a series of distributing pipes 44 of various lengths, each provided with a downturned end discharging into its respective portion of the top of the checker work, 70 75

whereby as the liquid passes down the checker work it will be well distributed and on account of the staggered relation of the bricks in the checker work, will form a large series of down-flowing films and rain, the liquid as it travels downward being brought into intimate contact with the hot gases of combustion, which travel upward, the liquid finally reaching the bottom of the concentration apparatus and during the normal operation of the apparatus, passing back to the respective settling tank, through the pipe 34 to be again lifted by the pump N or N¹ to the top of the concentration apparatus, thus making a continuous circuit repeatedly.

15 To the outlet pipe 40 of the pump N is connected a bleeder pipe 45, provided with a valve 46, this pipe extending to and connecting with the pipe 35 beyond its valve 37, as for example, at the T 47. When it is desired to discharge liquid 20 from the settling tank M to the corresponding evaporator L, the valve 46 may be opened, and valve 40¹ on pipe 40 may be closed whereupon the pump N will discharge direct to the evaporator, it being understood that the valve 37 is 25 normally closed. In case, however, it is desired to discharge directly from the bottom of the chamber 25 to the evaporator L the valve 37 is opened and the valve 46 is kept closed.

The settling tanks M are supplied with liquid 30 from the percolators by a pipe C³ connected to the discharge side of the pump c, suitable valves C¹², C¹³ being provided as shown in Figs. 1 and 1a.

The percolators C are alike. Each consists of a vat having a false bottom consisting of two 35 screens, the upper one 52 of finer mesh than the lower one 53, whereby a chamber is formed below the screens, as shown in Fig. 4. The solids to be treated rest on the uppermost screen 52. As before described, these solids are supplied to 40 the respective vats by the conveyer 14 which is of the usual distributing conveyer type so arranged that its bottom can be opened opposite any vat, or closed to allow the material in the conveyer to be passed along further. As the details of these distributing conveyers are old and well known, these details have not been illustrated in the drawings. The lower screen 53 is made strong enough to support the maximum load of carbonaceous material which may be placed in 50 the vat, without any appreciable sagging, the upper one being of fine enough mesh to prevent the passage of any appreciable amount of fine solids, it being expected that during the percolation step the lower part of the bed of material 55 resting on the screen will act as a filter bed to prevent the finer dusts from passing through the screens. An outlet c³ is connected to the chamber beneath the screen, the outlet from each vat being connected to the common suction pipe c⁴ 60 of the pump c. Each outlet pipe c³ is provided with a valve, as indicated at c⁵. Each vat is provided with an individual supply pipe c⁶ provided with a valve c⁷, these supply pipes being connected to the discharge pipe c⁸ of the pump c. 65 By means of the pump and the connections described, the solution in any vat can be pumped to any other vat, by suitable adjustment of the valves, as will be obvious to those skilled in the art.

70 In order to provide a supply of water for the vats, each is provided with a water supply pipe, as indicated at c⁹ which branch from a water main c¹⁰, suitable valves c¹¹ being employed to control the individual water supply pipe, as indicated. In the embodiment shown in the draw-

ings a distributing device or sprinkler c² is provided for each vat, each consisting of a central pipe and a plurality of branch pipes or arms, the latter being perforated on their undersides. By means of these sprinklers, the water from the water main may be sprinkled or well distributed over the carbonized residues in the vats when first supplying the water to the vats. Then the sprinkler may be disconnected from the water supply system and connected to the pipe c⁶, removing the down-turned nozzle if it is in place, and therefore, the sprinkler can serve to distribute any solution pumped to a vat from another vat.

In practice it has been found that such a sprinkler device is not really necessary, although perhaps a slight advantage. This is because the carbonized material from the carbonizing kiln is so porous that any means of filling the water into the vat on top of the carbonized material is entirely satisfactory on account of the almost immediate solution of the potassium and other soluble compounds as soon as the solid material is immersed.

When a vat is charged with water, and has stood for a few minutes, the solution may be drawn off and pumped to another vat whose solution has been withdrawn. In this way the solution is pumped from vat to vat in series, gradually increasing the concentration of the solution to the desired maximum. When this point has been reached the solution in its desired maximum concentration may be pumped off and discharged to suitable storage tanks until the concentrating apparatus requires a supply, or if the settling tanks are large enough, the concentrated solution may be pumped to them. In the drawings, the discharge side of the pump c is provided with a discharge pipe C³ which has branches c¹¹, each having a valve c¹², whereby the solution may be pumped to either one or both of the two settling tanks M, M¹, Fig. 1.

The vats may be operated in series as follows: One vat having been filled with carbonized residues, is supplied with fresh water. Then the solution may be pumped to the vat next to it, which had been filled with carbonized residues, and fresh water supplied to the first. The solution in the second vat may then be pumped to a third vat containing fresh carbonized residues, the weaker solution in the first vat pumped to the second vat, and fresh water again supplied to the first vat. This method of moving the solutions forward and supplying the first vat with fresh water is continued until the carbonized residues in the first vat have been supplied, or washed, with about five charges of fresh water. The strongest solution may then be pumped off to be concentrated; the several weaker solutions moved successively to the next vat ahead, and the extracted carbonized residues may then be discharged from the first vat. This same vat is then charged again with fresh carbonized residues and supplied with the stronger solution in the circuit; the other weaker solutions moved forward successively, and fresh water supplied to the weakest. In practice the initial solution supplied to each freshly filled vat may be pumped off to be further concentrated, the washings may consist of several successively weaker solutions with a final washing of fresh water, and the operations may be so timed that fresh carbonized residues are supplied to one vat during the period that the extracted carbonized residues are

being discharged from the vat next in line. In the vats the solids are treated with water to extract all their water-soluble contents, principally potassium and sodium salts with some potassium and sodium hydroxides including, as a particularly dangerous ingredient, a very small proportion of potassium cyanide. By pumping the solution from one vat to another, the concentration of the solution is gradually increased, until finally the solution is removed and put in storage for further treatment or sent to the proper settling tank M or M¹ of the preliminary concentrating apparatus. Usually there are some fine solids in suspension in the solution and these will tend to settle out in the settling tank as a sludge, which can be shoveled out from time to time and can be returned to the extracting or percolating apparatus.

As the settling tank is gradually filled it finally overflows its partition 39 and fills the small compartment connected with the pump. Let it be assumed that the concentration apparatus comprising the settling tank M and the scrubber H is to be used first. Valves 46 and 37 being closed, the fan K is put in operation. This draws the hot gaseous products of combustion from the combustion chamber B, through the flue l², through the tubes l⁴ of the evaporator L, through the duct l, and through the checker work of the scrubber H to the top of the latter, the fan discharging through the fan outlet k² to the atmosphere. The pump N is set in operation simultaneously with the starting of the fan K whereby the liquid solution from the tank M is pumped to the distributor tank P and from there fed to the various branch pipes 44 which distribute the solution, in a reasonable approach to uniformity, over the top of the checker work, down which it travels, sometimes as films on the bricks, sometimes as a shower or rain when falling through the spaces between the bricks, owing to the staggered relation of the bricks in the various courses. On its way down, the finely subdivided solution meets the ascending current of hot gases, which are rich in CO₂. As a result the water in the solution is gradually evaporated as it descends, and at the same time any inorganic compounds in the solution which will react with CO₂ are carbonated, such for example, as potassium hydroxide and particularly potassium cyanide. The latter has its acid driven off but in such great dilution with the large amount of gaseous products which escape from the scrubber, that no serious effects will result from the discharge of such mixture into the open air.

The solution, increasing in concentration of inorganic salts as it travels downward because of the removal of its moisture by the hot combustion gases, finally reaches the bottom of the scrubber H and passes back to its settling tank M through the pipe 34, the valve 36 being open at this time. The returning concentrated solution deposits in the settling tank as sediment the dust which it has washed out of the gases coming from the combustion chamber and causes a continual flow of the upper layer of clean liquid over the partition to the pump suction. In this way there is a continuous circulation of the liquid through the scrubber and settling tank, with a continuous removal of values from the gases, a continuous carbonation of those compounds in the solution which can be carbonated, and a continuous evaporation and removal of water from the solution, thereby rapidly concen-

trating the solution to the desired point. When the solution has reached a concentration where it is difficult to handle further by the pump and before it has reached the stage of depositing solids in the scrubber, the process is stopped in 5 the concentrating apparatus at that time in use, and the other concentrating apparatus is started. This is done by stopping the fan K and simultaneously starting the fan K¹ and the pump N¹, the valve 46 being opened so that the pump N 10 will pump the concentrated solution from settling tank M to the evaporating pan L, the latter having been drained of any fresh water it contains if such were used at the initial operation to prevent burning of the tubes in such pan. 15

When the pan L is filled with solution from the tank M it stands out of operation, while the other concentrating apparatus is operating in the same manner as hereinbefore described in connection with the first mentioned concentrating 20 apparatus. In other words the two concentrating apparatuses and the respective evaporating pans work in alternation, thereby maintaining a substantially continuous discharge of the gases from the combustion chamber B. 25

While the first mentioned concentrating apparatus is out of operation, its settling tank M receives a new charge of weak solution from the extractors, or from a storage tank, if such is used, and is ready for operation again as soon as the other concentrating apparatus has completed its work and is ready to be put out of operation.

On the next operation of the apparatus including the tank M and scrubber H, the gases from the combustion chamber B on their way to the scrubber H pass through the tubes of the evaporating pan L which is now charged with a strong solution. Thereupon, the evaporator operates to concentrate the strong solution to 35 crystallize out the salts. The evaporating pans are so proportioned that they will hold all the strong solution made at the prior run of the associated concentrating apparatus and will evaporate its charge to the full extent before the apparatus with which it is associated is shut down. 40 When this occurs, the evaporating pan is discharged by allowing its contents to flow, intermittently, to the centrifuge F¹, the solids for the most part being removed from the pan by 45 stirring so that they are carried in suspension to the centrifuge. Any solids which do not flow out may be removed from the pan by suitable means, as by scoops or shovels, and thus transferred to the centrifuge. 50

The centrifuge F¹ is provided with a suitable electric motor for driving it. The pipes for withdrawing any suspension or sludge in the respective evaporators are indicated at p¹, p², respectively, each pipe being controlled by a valve as shown. The mother liquor from the centrifuge, freed from any solids which can be thrown out by centrifuge action, is discharged by gravity to a small tank, not shown, from where it may be pumped to a storage tank for cooling to deposit further solid salt, or to the evaporator then in use, or, as indicated in Fig. 1, back into the system by way of the settling tank, through pipe f¹ and pump N. 60

The solids from the evaporating pan after 65 passing through the centrifuge are in excellent marketable condition, being relatively dry salts free from deliquescent material and from cyanides. The principal and most valuable con- 70

stituents are potassium salts which can be marketed without further refining at a price above the cost of production, so that the process is commercially satisfactory.

Referring again to the extractors, the solids removed from the vats are wet granular material containing very porous fixed carbon, in the granules of which is disseminated alkaline earth compounds such as calcium or magnesium compounds, practically all in the form of carbonate. This product when dried is very suitable as a soil conditioner for agricultural purposes and as a case hardening material, as hereinbefore explained. To dry the product it is fed onto the traveling belt 15 of the predryer and carried along through the atmosphere of hot gases, which can be supplied either from the combustion chamber, B, through the duct 17² or from the calcining kiln E, if the latter is in use, through the duct 17¹. The dried product is deposited by the belt in the conveyer d¹, which may deposit the product in a suitable receptacle.

Where, however, it is desired to treat the product further to calcine the alkaline earth carbonate to oxides, the conveyer d¹ is arranged to discharge into feed conveyer e, which continuously feeds the material to the rotary calcining kiln.

As the granular carbonaceous material travels down the inclined rotary kiln, which is rotated through the usual ring gear as shown in Fig. 1, the carbon is ignited and gradually consumed. The ignition is started initially by an oil burner or torch, not shown. Thereafter the incandescent material in the kiln serves to ignite the incoming material. Air is supplied in sufficient quantity at the lower end of the kiln to maintain an intense heat which is sufficient to convert the carbonates of calcium and magnesium to oxides. It is to be noted that the quantity of fixed carbon is more than sufficient to convert all the carbonates to oxide and the excess is sufficient to predry the wet solids on their way to the calcining kiln. Hence, it becomes possible to recover the oxides of calcium and magnesium which were used in the nicotine extraction process, so that such oxides may be converted to hydroxides and again used in the recovery of further nicotine, this being done at so low a cost that there is an appreciable saving in the cost of the lime as prepared in this way, which serves to reduce the cost of nicotine production.

The ash is discharged from the calcining kiln to one or the other of two vats, indicated at G¹ and G². When the ash, which is chiefly calcium oxide, is to be used for liming waste tobacco material at the extraction plant, water may be supplied to the vat G¹ or G² as soon as it has received a sufficient charge of ash, and the solution thus made is run off to the liming vats of the nicotine extraction plant, thereby completing the cycle of operations of such lime.

When one of the vats is being used for making solution, the other is being charged with ash from the kiln, the two vats working alternately.

Although in the specific description of the process and apparatus the starting material has been specified as waste tobacco, there are some other starting materials which have characteristics similar to those of tobacco which may be used. All such materials suitable for treatment by the steps of the process must have a relatively high percentage of potassium compounds and of constituents which when heated will evolve combustible

volatile material, since it is the heat derived from the combustion of these volatiles which is relied upon to make the process commercially practicable. There are a number of waste materials from land plants which may be used successfully in accordance with the present invention, for example, cotton hulls.

What is claimed is:

1. The process of recovering values from land-plant material having a relatively high content of potassium compounds and also of constituents which when heated will evolve a relatively large amount of volatile combustible material, which consists in progressively feeding such material through a heated zone whose temperature increases in the direction of travel of the material to a point whereby volatile combustible products are evolved, burning a portion only of said volatile combustible products in contact with the plant material, with controlled restricted access of air, to carbonize the material as it reaches the hottest part of the zone, leading off the products of such combustion mixed with the unburned portion of the volatile combustible material, supplying additional air to such mixture while it is still hot, to complete the combustion of the mixture out of contact with the plant material and produce high temperature combustion products rich in CO₂, progressively removing the carbonized material as soon as it has been freed of its volatiles and before its fixed carbon is consumed, extracting the water-soluble compounds from the carbonized products, separating the solution from the solids, and driving off the moisture of the solution from its solids by the heat of said hot combustion products.

2. The process of recovering values from land-plant material having a relatively high content of potassium compounds and also of constituents which when heated will evolve a relatively large amount of volatile combustible material, which consists in progressively feeding such material through a heated zone whose temperature increases in the direction of travel of the material to a point whereby combustible products are evolved, burning a portion only of said volatile combustible products in contact with the plant material, with controlled restricted access of air, to carbonize the material as it reaches the hottest part of the zone, leading off the products of such combustion mixed with the unburned portion of the volatile combustible material, supplying additional air to such mixture while it is still hot, to complete the combustion of the mixture out of contact with the plant material and produce high temperature combustion products rich in CO₂, progressively removing the carbonized material as soon as it has been freed of its volatiles and before its fixed carbon is consumed, subjecting the said carbonized material to the action of water to extract the water-soluble compounds from the carbonized products, separating the solution thus obtained from the solids, bringing the hot combustion products aforesaid into direct contact with the solution in subdivided form whereby the CO₂ reacts with certain of the inorganic compounds in the solution to carbonate the same, and water is driven off from the solution to concentrate it, and finally evaporating the concentrated solution to crystallize out the salts.

3. The process of recovering values from waste tobacco residues from a nicotine extraction plant, said residues containing alkaline earth compounds, which consists in progressively feeding such residues through a heated zone whose tem-

perature increases in the direction of travel of the residues to a point whereby volatile combustible products are evolved, burning a portion only of said volatile combustible products in contact with the residues, with controlled restricted access of air, to carbonize the residues as they reach the hottest part of the zone, leading off the products of such combustion mixed with the unburned portion of the volatile combustible material, supplying additional air to such mixture while it is still hot, to complete the combustion of the mixture out of contact with the residues and produce high temperature combustion products rich in CO₂, progressively removing the carbonized material as soon as it has been freed of its volatiles and

before its fixed carbon is consumed, subjecting the said carbonized products to the action of water to extract the water-soluble compounds from the carbonized products, separating the solution from the solids, driving off the moisture of the solution from its solids by the heat of said hot combustion products, drying the solids from the extraction step, igniting said solids with a free supply of air to burn all the fixed carbon and thereby convert the alkaline earth compounds to oxides and provide an excess of heat and utilizing the excess heat to dry further solids obtained from the extraction step.
